PANIC EXIT UNIT

John R. Foster, Indianapolis, Ind., assignor to Vonnegut
Hardware Company, Indianapolis, Ind., a corporation of Indiana

Filed Apr. 18, 1963, Ser. No. 74,509

Term of patent 14 years

(Cl. D10—8)

FIG. 1 is a perspective view of a panic exit unit embodying my new design;

FIG. 2 is a front elevational view thereof, with the actuator bar shown broken off along its length for convenience of illustration only; and

FIG. 3 is a sectional view taken substantially on the line 3—3 of FIG. 2 and looking in the direction of the arrows.

I claim:

The ornamental design for a panic exit unit, as shown and described.
